UNITED STATES PATENT OFFICE.

HENRY HEATH, OF NEW YORK, N. Y., ASSIGNOR TO FISK, CLARK & FLAGG,
OF SAME PLACE.

DESIGN FOR A SCARF.

SPECIFICATION forming part of Design No. 16,791, dated July 13, 1886.

Application filed May 20, 1886. Serial No. 202,811. Term of patent 14 years.

To all whom it may concern:

Be it known that I, HENRY HEATH, of the city, county, and State of New York, have invented a new and original Design for Scarfs, 5 of which the following is a full and exact description, reference being had to the accompanying drawing, and to the letters of reference marked thereon, making a part of this specification.

10 This design for a scarf consists in the novel configuration thereof illustrated in the drawing, and which presents the appearance, as therein delineated, of two extended parallelograms, A and B, of different widths and lengths, bounded laterally by the parallel lines C D C' 15 D', and whose straight lateral lines C C' on one side and D D' on the other are connected by intermediate curved lines, E E, completing

the design. The form of the outer ends, F F, of the parallelograms A and B may be square, ²⁰ as shown in the drawing, or pointed or rounded, without departing from my invention.

I claim as my invention—

The design for the configuration of a scarf herein shown and described, the same consisting of the two sets of parallel side lines, C D and C' D', at different distances apart, and the intermediate curved lines, E E, connecting them. ²⁵

In testimony whereof I have signed my name ³⁰ to this specification in the presence of two subscribing witnesses.

HENRY HEATH.
